NORTON T. KESLER AND THEODORE FORBY, OF ZION, ILLINOIS

COTTON PICKING DEVICE

Application filed September 30, 1929. Serial No. 396,364.

Our invention relates to improvements in cotton picking devices, and it consists in the combinations, constructions, and arrangements herein described and claimed.

5 An object of our invention is to provide a cotton picking device in which novel finger means is provided for picking cotton from balls and in which means is provided for effectively manipulating the fingers in such a manner that a maximum amount of cotton

10 is removed from the plant.

A further object is to provide a cotton picking device employing a tube for conveying the picked cotton, and in which novel means is provided for actuating the finger means and for cooperating with other means within the tube for moving the cotton rearwardly within the tube.

15 A further object is to provide a cotton picking device in which the number of moving parts has been reduced to a minimum and in which the parts are so arranged that the latter offer a minimum of resistance to the cotton moving within the tube, thereby providing a device which is relatively free from danger of plugging and the like.

A further object is to provide a cotton picking device of a type arranged to be easily and quickly opened for inspection, etc.

20 Other objects and advantages will appear in the following specification, and the novel features of the invention will be particularly pointed out in the appended claims.

Our invention is illustrated in the accompanying drawings, forming part of this application, in which

Figure 1 is a side elevation of our device.

Figure 2 is a fragmentary detail view of a portion of our device,

25 Figure 3 is a sectional view taken along the line 3—3 of Figure 2,

Figure 4 is a complement of the structure shown in Figure 2,

Figure 5 is an enlarged detail view of the finger-actuating mechanism,

Figure 6 is a detail view of one of the fingers.

Figure 7 is an enlarged sectional view of our device taken along the line 7—7 of Figure 4,

Figure 8 is a transverse sectional view taken along the line 8—8 of Figure 2,

Figure 9 is a sectional view taken along the line 9—9 of Figure 2, and

Figure 10 is a diagrammatic view of a bag which may be used in conjunction with our device.

In carrying out our invention, we make use of a tube 1 comprising sections 2 and 3. These sections are hinged together as at 4. One end of the tube is provided with a flange 5, the purpose of which will be defined more fully hereinafter. The tube is provided with a plurality of ribs 6, see Figures 1, 5, and 7. The ribs are spaced apart and provide bearing means for a gripping member 7. The tube is provided with a plurality of slots 8 which are cut in the tube between the ribs 6. The slots are somewhat shorter than the ribs, as shown in Figure 4, see also Figure 5. A plurality of fixed racks 9 is disposed within the tube. The racks are preferably provided with flange portions 10, see Figures 7 and 8, for permitting the racks to be rigidly secured to the tube.

The teeth associated with the racks are inclined rearwardly and in the direction of the longitudinal axis of the tube. In referring to Figure 2, it will be noted that the major portions of the racks are provided with relatively large teeth, as shown at 11, and that the front ends of the racks are provided with relatively small teeth as at 12. All of the teeth, however, are shaped for permitting cotton which is pulled into the tube to be moved rearwardly and to resist any movement of the cotton in the opposite direction. The forward end of the tube is also provided with a plurality of slots which are indicated at 13 in Figures 1 and 5. These slots are aligned with the slots 8. A plurality of movable rack members 14 is alternately disposed between the racks 9. The teeth associated with the movable racks are identical in construction with the teeth associated with the racks 9. In Figure 5 we have shown a detail view of one of the movable racks and their associated mechanism. Since all of the movable racks are identical in con-

struction, the description at this time will be confined to a single rack.

In referring to Figure 5, it will be noted that the rack 14 is provided with a slot 15 near the rear end. A pin 16 which is carried by lugs 17 which are disposed upon opposite sides of the rack projects through the slot. Thus it will be seen that the pin tends to support the rack and that the guides 17 cooperate with the pin in guiding the rack during its movement. Sliding guide members 18 and 19 are disposed within the tube and associated with the slots 8 and 13, respectively.

In referring to Figure 7, it will be noted that the guide member 18 is U shaped as at 20 for receiving a portion of the rack 14. Washers 21 may be disposed between the guide and the rack. A pin 22 passes through the guide, the washers, and the rack. The latter is provided with a slot through which the pin passes for permitting a certain amount of longitudinal movement of the pin with respect to the rack.

The rack is also provided with a recess 23 within which a portion of the guide 18 is disposed which cooperates with the slot in the rack during longitudinal movement of the guide with respect to the rack.

In referring to Figures 5 and 7, it will be noted that the gripping member 7 is operatively connected with the guides 18 by means of screws or bolts 24. A portion of each of the guides projects through the slots 8 for permitting the gripping member which has bearing contact upon the ribs 6 to be connected with the guides.

Let us again consider Figure 5. The guide 19 projects through the slot 13 and is partly disposed within a recess 25 which is formed in the rack 14. The recess is shown in detail in Figure 6. The rack is provided with a slot 26 through which a pin 27 passes. The latter is connected with the guide 19. The guide member 18, see Figure 5, is operatively connected with the guide 19 by means of bars 28 which are disposed upon opposite sides of the rack 14. The relation between the bars and the guides 18 and 19 is shown in Figures 7 and 8. Any movement of the gripping member 7 will cause a relative movement of the guides 19 through the medium of the bars 28 which are connected with the guides 18.

In Figures 5 and 6 we have shown a finger 29 as being operatively connected with the rack 14. A finger is associated with each of the moving racks. The fingers are identical in construction and the description of this part of the device will also be confined to a unit. The finger is substantially U shaped in construction and is provided with inclined edges 30 having progressively enlarged teeth from front to rear. The finger shown in Figures 5 and 6 is pivotally mounted at 31

upon the end of the sliding rack. The rack is slotted as at 32 for receiving a pin 33 which passes through the finger. Thus it will be seen that the finger may move in an oscillatory path by reason of the pivot 31 and the slot 32.

The finger is operatively connected with the guide 19 through the medium of links 34. In referring to Figure 8, it will be noted that the pins 27 pass through the links for connecting the latter with the guides. The opposite ends of the links are operatively connected with the fingers through the medium of the bolts 33. Thus it will be seen that movement of the bars 28 will cause an oscillatory movement of the fingers, the direction of movement depending upon the direction in which the gripping member 7 is moved. A movement of the gripping member 7 in the direction of the flange 5 will cause the fingers to be moved from the full line position shown in Figure 5 to the dotted line position. When, however, the gripping member 7 is moved in the opposite direction, the fingers will be moved in opposite directions; that is to say, from the dotted line position to the full line position.

In Figures 2 and 4 we have shown a plurality of lugs 35 which are secured to the tube for supporting and guiding the movable racks and the bars. The sliding guide members 19 are connected with a ring 36 by means of screws or bolts 37. Thus it will be seen that the movable racks are rigidly tied together, but at the same time are mounted for movement simultaneously as a unit.

From the foregoing description of the various parts of the device, the operation thereof may be readily understood. The tube is of sufficient length to permit cotton to be picked from the plants with a minimum amount of stooping. Reciprocation of the gripping member 7 will cause a movement of the fingers 29 into and out of the end of the tube 1. In Figure 1 we have shown the fingers as projecting from the tube. The fingers so projecting are in their grasping positions. At this time the gripping member 7 has been moved forwardly to its extreme position. When the gripping member is moved rearwardly, the fingers 29 move toward the longitudinal axis of the tube 1 and into the tube.

When the gripping member 7 has been moved rearwardly to its extreme position, the fingers 29 will be entirely enclosed within the tube. The movement of the fingers 30 about their axes 31 is determined by the length of the slots 23 and 25. When the movable racks are positioned as shown in Figure 5 and the gripping member 7 is moved rearwardly, the fingers 29 will immediately begin their movement from the full line position to the dotted line position. Similarly, when the gripping member 7 is moved forwardly, the fingers will tend to spread outwardly. During the move-

ment of the fingers from the tube, the spreading will be completed. Thus it will be seen that the fingers are positioned for grasping a ball of cotton, and, when the gripping member 7 is moved rearwardly, the cotton will be pulled into the tube. As soon as the cotton reaches the interior of the tube, the teeth associated with the fixed racks will prevent the cotton from being moved outwardly when the fingers are being positioned for grasping another ball. Each time the movable racks are reciprocated, the cotton within the tube will be moved rearwardly a certain distance.

The gripping member 7 is rigidly connected with the guides 18 while the latter are directly connected with the bars 28. These bars are in turn connected with the guides 19 and the latter are connected with the links 34. The links are in turn connected with the fingers 29. The racks 14 are slotted for receiving the pins 27, 28, and 33. For this reason, the fingers 29 are positively actuated at all times. The slots are proportioned in such a manner that the fingers may be positively moved from the full line position shown in Figure 5 to the dotted line position upon a slight movement of the gripping members 7. When the fingers are in their expanded positions a slight movement rearwardly of the gripping member 7 immediately moves the fingers from their expanded positions to their contracted positions. A continued movement of the gripping member shifts the movable racks rearwardly within the tube together with the fingers for shifting the cotton rearwardly with respect to the stationary racks.

Thus it will be seen that during the continued operation of the device, the cotton will finally be ejected from the rear end of the tube. This end is preferably connected with one of the sleeves 38 associated with a bag 39 which may be carried by the operator of the device. For convenience, the bag may be provided with a bottom which is easily opened, whereby when the bag is filled, the cotton may be removed therefrom. Preferably, the bags should be provided with two sleeves so that the device may be connected with either one of the sleeves, depending upon whether or not the operator is right- or left-handed.

In referring to Figure 7, it will be noted that the tubular member may be opened, whereby all of the parts within the device are easily accessible. It will also be noted that the stationary and movable racks are so arranged that an equal number of these elements is associated with each part of the tube when in its opened position.

One of the sections of the tube is provided with a plurality of spring members 40 which are aligned with lugs carried by the other member. The construction is such that when the two pieces are moved together the sections are locked together as shown in Figure 3. The springs are sufficiently flexible to per-

mit the two pieces to be easily locked together and at the same time easily opened up as when repairing or inspecting the interior mechanism. Before the device is opened up, however, the ring 36 and the gripping member 7 are removed from the tube. In referring to Figure 8 it will be noted that the ring is provided with recesses for permitting the latter to be pushed over the hinges and the spring members 40. The gripping member 7 is of sufficient diameter to permit the latter to be easily removed. The ribs 6, of course, provide bearing surfaces for the gripping member.

We claim:

1. A cotton picking device comprising a tubular member consisting of hinged together portions, movable and stationary cotton-moving elements longitudinally disposed within said tubular member, finger means associated with the movable elements and arranged to be moved for picking cotton and pulling the same within the tubular member, and means associated with the tubular member and operatively connected with the movable cotton-moving elements for operating the same.

2. A cotton picking device comprising a tubular member consisting of hinged together portions, movable and stationary cotton-moving elements longitudinally disposed within said tubular member, finger means associated with the movable elements and arranged to be moved for picking cotton and pulling the same within the tubular member, means associated with the tubular member and operatively connected with the movable cotton-moving elements for operating the same, and means for holding said hinged together portions securely together.

3. A cotton picking device comprising a tubular member consisting of hinged together portions, movable and stationary cotton-moving elements longitudinally disposed within said tubular member, finger means associated with the movable elements and arranged to be moved for picking cotton and pulling the same within the tubular member, means associated with the tubular member and operatively connected with the movable cotton-moving elements for operating the same, means for holding said hinged together portions securely together, and a receptacle associated with said tubular member for receiving cotton passing through the latter.

4. A cotton picking device comprising an elongated tubular member having a group of longitudinal slots provided near each end, a plurality of movable cotton-moving elements longitudinally disposed within the tubular member and having means projecting through said slots, a gripping member disposed upon the tubular member and operatively connected with the means projecting through one of said groups of slots, ring means disposed upon the tubular member and

operatively connected with the means projected through the other of said groups of slots, stationary cotton-moving elements longitudinally disposed within the tubular member and in operative relation with the movable elements, finger means movably connected with the movable elements and operated when said gripping member is moved for picking cotton and pulling the same within the tubular member and moving the cotton into engagement with the movable and stationary cotton-moving elements, and a receptacle operatively connected with one end of the tubular member for receiving cotton passing through the device, said tubular member comprising hinged together portions.

5. A cotton picking device comprising a hollow member having longitudinal slots therein, a plurality of longitudinally arranged toothed members rigidly connected with the hollow member upon the interior thereof, a plurality of longitudinally arranged movable toothed members alternately positioned between the first named toothed members, cotton picking fingers pivotally connected with adjacent ends of said movable toothed members, a gripping member movably mounted upon said hollow member, a plurality of bars, means extending through the slots in the hollow member for operatively connecting said bars with the gripping member, and means operatively connecting the bars with the movable toothed members 35 and fingers whereby said movable toothed members and fingers may be moved when the gripping member is actuated.

6. A device of the type described comprising a tubular member having spaced-apart longitudinally arranged toothed members fixedly disposed within the tubular member, longitudinally arranged toothed members movably disposed within the tubular member, said fixed toothed members and movable toothed members being alternately positioned, toothed fingers pivotally connected with adjacent ends of said movable toothed members, an actuating member slidably mounted on the tubular member, bar members disposed within the tubular member, means extending through longitudinal slots in the tubular member for operatively connecting the bar member with the actuating member, and means operatively connecting the bars with the movable toothed members and fingers whereby said movable toothed members and fingers may be moved when the gripping member is actuated, said toothed fingers being adapted for being actuated prior to the actuating of the movable toothed members.

Signed at Chicago, in the county of Cook, and State of Illinois, this 25th day of September, A. D. 1929.
